DESIGN FOR A BOTTLE

Leonid de Lescinskis, New York, N. Y.

Application July 30, 1948, Serial No. 147,853

Term of patent 14 years

(Cl. D58—9)

To all whom it may concern:

Be it known that I, Leonid de Lescinskis, a citizen of the United States, residing at New York, in the county of New York and State of New York, have invented a new, original, and ornamental Design for a Bottle, of which the following is a specification, reference being had to the accompanying drawing, forming a part thereof.

In the drawing:

Fig. 1 is a front elevational view of a bottle, showing my new design;

Fig. 2 is a top plan view;

Fig. 3 is a bottom plan view; and

Fig. 4 is a side elevational view of the same.

I claim:

The ornamental design for a bottle, as shown.
LEONID DE LESCINSKIS.
